CENTRIFUGAL GOVERNOR

Umberto Quintavalle, Milan, Italy, assignor to
 Fabbrika Italiana Magneti Morelli Soc. An.,
 Milan, Italy, a corporation of Italy

Application July 14, 1936, Serial No. 90,607
 In Italy July 22, 1935

9 Claims. (Cl. 64—25)

This invention relates to centrifugal governors adapted to control the ignition advance in internal combustion engines and for other appliances and it relates more particularly to the governors 5 of the kind in which each centrifugal mass consists of a number of sections and a set of said sections act directly on the governor controlled member while the other sections have a lost motion cooperation with said directly-acting sections 10 and are arranged to become progressively inoperative in the course of the governor operation.

The present invention has for its object a centrifugal governor of the above stated class in 15 which the sections of each centrifugal mass are all pivoted around a single pivot axis and each of said sections adapted to operate directly on the governed member is engaged therewith positively and reversibly that is in both angular directions, such engagement being preferably made by means of a toothed quadrant of a mass section meshing with a toothed portion of said governed member.

By the above outlined arrangement a progressive operation of the sectioned masses is secured and at the same time the construction and operation of each centrifugal mass are made very simple in view of the mounting of the whole sections of each separate mass on a single pivot.

30 Further the positive engagement of each centrifugal mass in both angular directions with the controlled member causes the operation to occur always under the same conditions and in the most efficient manner.

35 An embodiment of this invention is illustrated by way of example on the annexed drawing and Figure 1 is a central section on line 1—1 of Fig. 2 with some portions removed,

Figure 2 is a section of the governor along a 40 plane perpendicular to its axis, the said section being made on line 2¹ of Fig. 1 in its right hand half portion and on line 2 of Fig. 1 in its left hand portion,

Figure 3 is a separate plan view of one of the 45 mass sections which are positively engaged with said governor controlled member,

Figure 4 is a separate plan view of one of the lost motion operative mass sections,

Figure 5 is a separate plan view of another of 50 said lost motion operative mass sections, and

Figure 6 is a separate plan view of a locking mass section.

The governor includes a cylindrical casing 1 fast with a driving or driven member 2.

55 3 is a shaft, respectively a driven or driving one,

which is aligned with casing 1 and has a toothed pinion 4 integral therewith and positioned within said casing 1.

Each centrifugal mass consists of a number of sections 6, 7, 8 located adjacent to and alternating with each other and is pivoted on a pivot stud 5 fast with the casing 1 and parallel with the rotary governor axis.

The sections 6, 7, 8 are provided with a hole 9 for their pivotal mounting on the respective pivot 10 5 and they have similar shapes, as illustrated in Figures 3, 4 and 5, their respective essential difference being in their weight in order to secure as a progressive operation as possible.

The section 6 having the smallest weight (Figure 15 3) includes a toothed quadrant 6' which is in mesh with the teeth of the pinion 4; said section 6 has further a hole 10 through which a pin 11 intended to interconnect all the sections 6 comprising the mass extends.

The section 7 (Fig. 4) having a larger weight 20 has no toothed quadrant and in register with the hole 10 of sections 6 and accordingly in register with the location of pin 11 in the mass, said section has an arc-shaped slot 12 the centre 25 of said arc-shaped slot lying in the centre of hole 9; said slot 12 has an angular extent sufficient to provide a free deviation of sections 6 and pin 11 through a certain angle with respect to sections 7.

Finally the section 8 has a further heavier weight (Fig. 5) and it is similar to section 7 it having however an arc-shaped slot 13 whose angular extent is larger than that of slot 12 of section 7.

35 Sections of different classes as above described are alternating with each other in each mass, the arrangement being such as each section 6 having a toothed quadrant 6' in mesh with pinion 4 is located intermediate two toothless 40 sections as 7 or 8.

It is to be understood that a single class of toothless sections either as 7 or as 8 may be used, instead of embodying two different classes of sections deprived of teeth in mesh with pinion 4. 45

Each centrifugal mass includes a further section 14 located adjacent the assembly of sections 6, 7 and 8 (Fig. 6); said section 14 is loose on pivot stud 5 and beyond the range of the pin 11 assembling in the above described manner 50 the several sections of the mass.

The section 14 has a locking nose 14' adapted to engage either of the recesses intermediate teeth of pinion 4 as well as a finger 14'' acted on by a blade spring 15 which is engaged angu- 55

larly with pivot stud 5 and acts to move the section 14 into its position in which the nose 14' thereof is engaged with teeth of pinion 4.

The cylindrical wall of the casing 1 is provided with an annular lining 16 of soft material as rubber, adapted to damp the impact of parts 6, 7, 8, 14 when they are completing their outward stroke under the action of centrifugal force. Of course any other appropriate impact-damping means may be substituted for such a rubber lining.

In inoperative conditions the sections 6, 7, 8 of each mass are close to the rotary axis of the governor and the ends of the slots 12 and 13 of sections 7 and 8—nearest to the line connecting the axes of pivot pin 5 and of the shaft 3 are in contact with the pin 11 of the set of sections 6.

When the governor has taken a predetermined rotary speed the locking section 14 under centrifugal force spreads outwardly against action of spring 15 and removes its nose 14' from engagement with teeth of pinion 4 and permits for the governor operation.

During the outward radial displacement of parts 6, 7, 8, under the action of centrifugal force, each of sections 6 acts by its teeth 6' on teeth of pinion 4 to cause the required angular displacement between the driving member and the driven one, while sections 7 and 8 act in similar manner through the medium of the sections 6 because the ends of their slots 12 and 13 act on the pin 11 fast with the operative sections 6 of the same mass.

At the time the speed and centrifugal force have a certain value the sections 8 abut on the soft lining 16 of the cylindrical wall of the casing 1 or generally on the stop means restricting their outward deviation and consequently said sections 8 are not longer operative on the pin 11 and pinion 4; when a higher speed is reached sections 7 are similarly made inoperative the pinion 4 being thus driven only by the sections 6 when further higher speeds are obtained; finally also said sections 6 abut against the lining 16 of the casing 1 as shown in the right hand half in Fig. 2. Thus a progressive action of the several sections 6, 7, 8 of the masses is secured, and any predetermined rate of respective angular motion of parts 3 and 2 with increase of the speed of the driving member may be secured.

A reverse operation occurs when the velocity drops, that is the sections 6 tend to take again their normal position under the action of the resistant torque of the magneto and as the action of the centrifugal force is progressively reduced said sections progressively approach the axis of rotation of the governor and shift sections 7 and 8 in sequence with them.

Assuming that shaft 3 is the driving shaft and that it rotates counter-clockwise as seen in Fig. 2, when it is trailing with respect to driven member, the positive interengagement in both directions of the pinion 4 and mass sections 6 causes the motion of said sections towards the soft lining 16 until said sections 6 abut on said lining after the frictional resistance opposed to them by the sections 7 and 8 has been overcome, and consequently any impact and noise as could arise during the governor operation is prevented.

The frictional resistance against the motion of sections 6 may be increased by providing resilient means which force the several sections of each mass in frictional contact with each other. For such a purpose springs 15 may be availed of by giving them a proper bias both in

angular direction around pivot stud 5 and in the inward longitudinal direction with respect to said stud; otherwise such springs 15 may include an arm acting on lug 14" of section 14 and an underlying portion coiled around said pivot stud 5 to force the mass sections in contact with each other, said spring extending through a transverse hole of stud 5.

The locking members 14 are intended to prevent the governor operation before the rotary speed has taken a defined speed under which an erratic operation could develop.

When the speed comes down under such a defined speed the sections 14 are moved by their springs 15 in their operative position to lock again 15 casing 1 with pinion 4 and consequently the driven member with the driving one.

What I claim as my invention and desire to secure by United States Letters Patent is:—

1. A centrifugal governor for controlling the respective angular position of two aligned rotary members comprising a pivot fast on one of said rotary members and extending parallel with the axis of rotation thereof, centrifugal force responsive mass sections pivoted on said pivot, a toothed quadrant on at least one of said mass sections and a cooperating toothed part on the other one of said rotary members, cooperating lost motion interconnecting means in said mass sections, and means for limiting the outward deviation of all said mass sections.

2. A centrifugal governor for controlling the respective angular position of two aligned rotary members comprising a pivot fast on one of said members and extending parallel with the axis of rotation thereof, centrifugal force responsive mass sections pivoted on said pivot, engaging means on at least one of said mass sections and on the other one of said rotary members, said engaging means cooperating positively with each other in both angular directions, others of said mass sections having each an arc-shaped slot concentric with said pivot, said slots having different angular extents in the different ones of said second named mass sections, a pin projecting from said first named mass section and engaging said slots of said other mass sections with angular lost motion, and means for limiting the outer deviation of all said mass sections.

3. A centrifugal governor for controlling the respective angular position of two aligned rotary members comprising a pivot fast on one of said members and extending parallel with the axis of rotation thereof, centrifugal force responsive mass sections pivoted on said pivot, engaging means on at least one of said mass sections and on the other one of said rotary members, said engaging means cooperating positively with each other in both angular directions, cooperating lost motion interconnecting means in said mass sections, spring means forcing said mass sections into frictional engagement with each other, and means for limiting the outward deviation of all said mass sections.

4. A centrifugal governor for controlling the respective angular position of two aligned rotary members comprising a pivot fast on one of said members and extending parallel with the axis of rotation thereof, centrifugal force responsive mass sections pivoted on said pivot, engaging means on at least one of said mass sections and on the other one of said rotary members, said engaging means cooperating positively with each other in both angular directions, cooperating lost motion interconnecting means in said mass sec-

tions, a further mass section pivoted on the same pivot as other mass sections and loose with respect to all said mass sections, means on said loose mass section for releasably engaging the 5 said second named one of said rotary members, means for holding said loose mass section in engaging position until the angular speed of said rotary members has reached a minimum predetermined value, and means for limiting the outward deviation of all said mass sections.

5. A centrifugal governor for controlling the respective angular position of two concentric rotary members, one of said members being in the form of a cylindrical housing, comprising a pivot 15 fast in said housing member and extending parallel with the axis of rotation thereof, centrifugal force responsive mass sections pivoted on said pivot, engaging means on at least one of said mass sections and on the other one of said rotary 20 members, said engaging means cooperating positively with each other in both angular directions, cooperating lost motions interconnecting means in said mass sections, and a soft lining on the inside of the cylindrical wall of said housing 25 member for limiting the outward deviation of all said mass sections.

6. A centrifugal governor for controlling the respective angular position of two aligned rotary members comprising a pivot fast on one of said 30 members and extending parallel with the axis of rotation thereof, centrifugal force responsive mass sections pivoted on said pivot, engaging means on each of a number of said mass sections and on the other one of said rotary members, 35 said engaging means cooperating positively with each other in both angular directions, a pin interconnecting said mass sections having engaging means, others of said mass sections having each an arc-shaped slot concentric with said pivot, 40 said mass sections having engaging means and said mass sections having arc-shape slots being adjacent to and alternating with each other and said pin extending through all said slots, a further mass section pivoted on said pivot and loose with respect to all 45 said mass sections, means on said loose mass section for releasably engaging said engaging means of the second named one of said rotary members, means for holding said loose mass section with its nose in engaging position until the angular speed of said members has reached a minimum predetermined value, and soft means for limiting the outward deviation of all said mass sections.

7. A centrifugal governor for controlling the 55 respective angular position of two aligned rotary members comprising a pivot fast on one of said members and extending parallel with the axis of rotation thereof, centrifugal force responsive mass sections pivoted on said pivot, engaging means on each of a number of said mass sections and on the other one of said rotary members, said engaging means cooperating positively with each other in both angular directions, a pin interconnecting 60 said mass sections having engaging means, others of said mass sections having each an arc-shaped slot concentric with said pivot and said slots having different angular extents in several sets of last named mass sections, said mass sections having engaging means and said mass sections having arc-shaped slots being adjacent to and

alternating with each other and said pin extending through all said slots, a further mass section pivoted on said pivot and loose with respect to all said mass sections, a nose on said loose mass section for releasably engaging said engaging means of the second named one of said rotary members, spring means for holding said loose mass section with its nose in engaging position until the angular speed of said members has reached a minimum predetermined value, and soft 10 means for limiting the outward deviation of all said mass sections.

8. A centrifugal governor for controlling the respective angular position of two aligned rotary members comprising a pivot fast on one of said 15 members and extending parallel with the axis of rotation thereof, centrifugal force responsive mass sections pivoted on said pivot, a toothed quadrant on each of a number of said mass sections, teeth on the other one of said rotary members and in mesh with said mass section quadrants, a pin interconnecting said toothed quadrant mass sections, others of said mass sections having each an arc-shaped slot concentric with said pivot and said slots having different angular extents in several sets of last named mass sections, 20 said toothed quadrant mass sections and said arc-slotted mass sections being adjacent to and alternating with each other and said pin extending through all said slots, a further mass section pivoted on said pivot and loose with respect to all 25 said mass sections, a nose on said loose mass section for releasably engaging said teeth of the second named one of said members, spring means for holding said loose mass section with its nose 30 in engaging position until the angular speed of said members has reached a minimum predetermined value, and soft means for limiting the outward deviation of all said mass sections.

9. A centrifugal governor for controlling the 40 respective angular position of two aligned rotary members comprising a pivot fast on one of said members and extending parallel with the axis of rotation thereof, centrifugal force responsive mass sections pivoted on said pivot, a toothed quadrant on each of a number of said mass sections, teeth on the other one of said rotary members and in mesh with said mass section quadrants, a pin interconnecting said toothed quadrant mass sections, others of said mass sections having each 45 an arc-shaped slot concentric with said pivot and said slots having different angular extents in several sets of last named mass sections, said toothed quadrant mass sections and said arc-slotted mass sections being adjacent to and alternating with each other and said pin extending through all said slots, spring means forcing 50 said mass sections in frictional engagement with each other, a further mass section pivoted on said pivot and loose with respect to all said mass sections, a nose on said loose mass section for releasably engaging said teeth of the second named one of said members, spring means for holding said loose mass section with its nose in engaging 55 position until the angular speed of said members has reached a minimum predetermined value, and soft means for limiting the outward deviations of all said mass sections.

CERTIFICATE OF CORRECTION.

Patent No. 2,093,736.

September 21, 1937.

UMBERTO QUINTAVALLE.

It is hereby certified that the name of the assignee in the above numbered patent was erroneously written and printed as "Fabbrica Italiana Magneti Morelli Soc. An." whereas said name should have been written and printed as Fabbrica Italiana Magneti Marelli Soc. An., of Milan, Italy, a corporation of Italy, as shown by the record of assignments in this office; and that the said Letters Patent should be read with this correction therein that the same may conform to the record of the case in the Patent Office.

Signed and sealed this 21st day of December, A. D. 1937.

Henry Van Arsdale,

Acting Commissioner of Patents.
